D19681

UNITED STATES PATENT OFFICE.

WILLIAM W. GOODWIN, OF BORDENTOWN, NEW JERSEY.

DESIGN FOR A GAS-RANGE.

SPECIFICATION forming part of Design No. 19,681, dated March 4, 1890.

Application filed January 31, 1890. Serial No. 338,787. Term of patent 7 years.

To all whom it may concern:

Be it known that I, WILLIAM W. GOODWIN, a citizen of the United States, residing at Bordentown, Burlington county, State of New Jersey, have invented a certain new and original Design for Gas-Ranges, of which the following is a full, clear, and exact description, reference being had to the accompanying drawings, forming a part of this specification.

5 My invention relates to gas-ranges; and it consists of the novel configuration thereof in its several parts, as shown in the accompanying photograph, forming a part of this specification.

10 Its principal features are an upright frame

having three series of chambers arranged one above the other, the upper and lower being closed by doors uniting in the center and the central portion thereof divided into chambers.

20 I claim—

The design for a gas-range, substantially as shown and described.

In testimony whereof I have hereunto affixed my signature this 5th day of December, 25 A. D. 1889.

WILLIAM W. GOODWIN.

Witnesses:

ANDREW ZANE,
H. T. FENTON.
